C. A. MORIN

METHOD OF MAKING WELT SHOES

Filed Aug. 31, 1925

Fig. 1

Fig. 2

UNITED STATES PATENT OFFICE.

CHARLES A. MORIN, OF BOSTON, MASSACHUSETTS.

METHOD OF MAKING WELT SHOES.

Application filed August 31, 1925. Serial No. 53,512.

This invention involves certain improvements upon the shoe disclosed in my prior Patent, No. 1,587,787, granted June 8, 1926, and the method of producing such shoe 5 disclosed in my prior Patent, No. 1,528,260, granted March 3, 1925, to which reference is made as illustrating the particular type of shoe involved herein.

Shoes built in accordance with said 10 patents are characterized by a smooth, flat, level bearing or tread foundation, but where there is any variation in the weight of either the insole or the welting, or any irregularity in the stitching, such tread foundation may appear to be not wholly flat and level when the shoe is new and before it has been worn. This is due to the fact that the upper and lining have not yet dropped down to smoothness with the insole, but as soon as the shoe 20 is laced on the foot this condition is automatically remedied. The objection is, therefore, more fancied than real, but in order to overcome it I have devised my present invention.

According to it, the shoe when finished is 25 wholly smooth, flat and level on the inside and there is no trace or suggestion of even the slightest temporary seam or ridge at the juncture of the upper and lining with the insole. I accomplish this result by grooving 30 or otherwise counter-sinking the bottom of the last in the region which will underlie the juncture of the upper and lining with the insole when the shoe is lasted. This 35 groove permits the upper and lining to sink down to smoothness with the insole under the leveling pressure when the shoe is leveled, so that all possibility of even the 40 slightest trace of a temporary ridge or seam is obviated, with the result that even before the shoe is drawn on the foot and worn, the tread foundation is absolutely smooth, level and flat.

The method of practicing my invention, 45 together with a characteristic last for carrying out the principles involved, is described and illustrated in the accompanying specification and drawings, throughout which like reference characters are used to indicate corresponding parts. In the drawings:

Fig. 1 is a bottom view of a last in accordance with my invention, and

Fig. 2 is a cross section through the lasted upper.

50 In accordance with the method disclosed

in my prior patent, the insole 1 is channeled to produce a full feather, portions of which are subsequently removed in the region of the shank and ball portion of the insole, so that a portion of the edge face of the insole 60 extending the full thickness of the insole is definitely set in from the outer edge of the bottom face of the last L. The insole is also provided with the usual inner channel 2 extending a substantial distance below the 65 outer face of the insole.

According to my present invention, the bottom face of the last is grooved or otherwise counter-sunk as indicated at 3. This counter-sink corresponds to the insetting of 70 the edge face of the insole so that when the welt 4 and upper 5 are stitched at 6 (Fig. 2) within the inseam channel 2 of the insole and the shoe leveled, the upper (and lining, if the shoe is lined,) may sink down 75 in the groove or counter-sink 3 to smoothness with the insole, and present a tight smooth joint.

This results in the elimination of any 80 temporary ridge or seam at the juncture of the upper and lining with the insole, and even though such ridge automatically smooths out as soon as the shoe is drawn on the foot, my invention nevertheless is of 85 advantage in that it avoids possible criticism of the shoe as not being initially smooth and flat on the inside.

Various modifications in the form and construction of my device may obviously be resorted to without departing from the 90 spirit of my invention if within the limits of the appended claims.

What I therefore claim and desire to secure by Letters Patent is:

1. In the method of making a welt shoe 95 having a substantially flat tread foundation, that improvement which consists in providing a last having a countersunk portion in its bottom face and inset from its marginal edge, in temporarily fastening to said last a 100 channeled insole having a projecting feather, portions of which in the region of the ball and shank have been removed to bring the edge face of the insole at these points definitely within the marginal edge of the last, 105 in temporarily lasting an upper over the inset edge of the insole, in stitching a welt through the upper and the edge face of the insole, and in finally leveling the shoe to 110 press into said countersunk portion of the

+ last that portion of the upper overlying the same whereby to form a tight smooth joint with the insole on the inside of the shoe.

2. In the method of making a welt shoe having a substantially flat tread foundation, that improvement which consists in providing a last having a groove in its bottom face and inset from its marginal edge and extending about its fore part, in temporarily fastening to said last a channeled insole having a projecting feather, portions of which in the region of the ball and shank have been removed to bring the edge face

of the insole at these points definitely within the marginal edge of the last, in temporarily lasting an upper over the inset edge of the insole, in stitching a welt through the upper and the edge face of the insole, and in finally leveling the shoe to press into said groove of the last that portion of the upper overlying the same whereby to form a tight smooth joint with the insole on the inside of the shoe.

In testimony whereof I affix my signature.

CHARLES A. MORIN.
